UNITED STATES PATENT OFFICE.

WINSLOW R. PARSONS, OF CHICAGO, ILLINOIS.

RUFFLER.

SPECIFICATION forming part of Letters Patent No. 699,229, dated May 6, 1902.

Application filed December 2, 1899. Serial No. 738,964. (No model.)

To all whom it may concern:

Be it known that I, WINSLOW R. PARSONS, of Chicago, in the county of Cook and State of Illinois, have invented certain new and useful Improvements in Rufflers, of which the following is a specification.

This invention relates to improvements in rufflers for sewing-machines; and it has for some of its principal objects the production of a ruffler wherein the ruffler-blade and parts moving therewith are so mounted or supported as to avoid practically all rubbing together or friction between parts in the reciprocation of the blade, while at the same time the blade and connected parts are supported so as to reciprocate in a substantially rectilinear path and practically as though moving within guideways; to provide a ruffler wherein the throw or reach of the ruffler-blade bears a novel relation to needle and such throw is lengthened or shortened in a peculiar way best adapted to produce perfect ruffles; to provide an improved construction in that part of the ruffler constituting the presser-foot, which is adapted to coöperate with the ruffling-blade in such manner as to receive and hold more perfectly the fabric; to provide a simple and improved holding device for locking the adjustable tappet, and, in general, to simplify and improve the details of construction in such manner as to produce a convenient, practical, and extremely durable device of the character referred to.

The invention consists in the matters hereinafter set forth and more particularly pointed out in the appended claims, and the same will be readily understood from the following description, reference being had to the accompanying drawings, in which—

Figure 1 is a view in side elevation of a ruffler embodying my invention. Fig. 2 is a similar view of the device looking at the opposite side thereof. Fig. 3 is a plan view of the ruffler. Fig. 4 is a fragmentary view of the parts which are most immediately concerned in the formation of the ruffle shown in changed position from that shown in Fig. 2.

Referring to said drawings, A designates the base or frame plate of the ruffler, which in the particular embodiment shown herein is approximately L-shaped in plan view and provided with suitable means whereby it may

be rigidly attached to the particular machine for which the ruffler is designed, consisting in the present instance of a set-up portion *a*, formed integrally with the rear end of said plate or that end toward which the fabric moves when passing through the ruffler and provided with a slot or recess *a'* for engagement with a suitable set-screw or other holding device upon the machine.

A' A² designate a pair of standards arranged to rise from the base-plate, shown in the present embodiment as arranged near the respective ends thereof and approximately in longitudinal alinement with each other, one of said standards *A²* being formed integrally with the set-up portion *a*, while the other, *A'*, is formed integrally with the inner side margin of the body of the base-plate, as indicated clearly in the drawings.

B B' designate two pendulum-links respectively pivoted at their upper ends to the upper portions of the standards *A' A²*, the link *B* being secured to the right-hand side of the standard as viewed by the operator, so as to permit its lower end to swing past the set-up portion *a*, while the link *B'* is conveniently arranged at the opposite side of the standard *A²*.

C designates as a whole the ruffler-blade, which is arranged to occupy and reciprocate within the angle of the L-shaped base-plate and comprises a relatively rigid sheet-metal body *C'*, provided with upstanding ears *c c'*, with which are pivotally engaged the lower ends of the pendulum-links *B B'*, respectively, and to the under side of which body is rigidly attached the spring-metal ruffler-blade proper, *C²*. In the particular embodiment shown herein the ruffler-blade support *C'* is provided at its side margin adjacent to the base-plate with an integral extension *c²*, which is bent or set up adjacent to its union with the main body sufficiently to bring it above the top surface of the base-plate and is then extended horizontally rearward above said base-plate to its point of connection with the link *B'*, the said extension being deflected laterally sufficiently to avoid interfering with the standard *A²* in its reciprocation, as will hereinafter more fully appear.

D designates the separating-blade, which consists, as usual, of a thin spring sheet-metal blade arranged to underlie the ruffler-blade,

as shown, and is conveniently supported in position by means of a transversely-extending U-shaped support D', the upper arm of which, d, is adjustably secured to the upper 5 side of the base-plate at a point approximately opposite the standard A', while the other arm thereof, d', is returned beneath the base-plate and at some distance from the same transversely across and terminates at a point 10 approximately in line with the opposite side of the ruffler-blade, the separating-blade being rigidly attached to the under side of the said lower arm conveniently by being riveted thereto and arranged to extend thence longitudinally beneath the ruffler-blade. 15

The ruffler-blade proper, C², is arranged to extend obliquely downward and backward, so as to bear yieldingly against the separating-plate throughout its reciprocation, being 20 curved downward slightly to insure a more certain engagement of its toothed free end with the fabric and so shaped that it will maintain its pressure upon the fabric notwithstanding the slight rising-and-falling 25 movement of the ruffler-blade body incident to its reciprocation upon the link-supports.

Describing now the means whereby the ruffler-blade is reciprocated from the needle-arm, E designates a tappet-lever pivotally 30 attached between its ends to the upper part of the standard A', at the side thereof opposite that to which the pendulum-link B is attached, provided at its rearwardly-extending end with the usual yoke e, adapted for engagement 35 with a suitable projection upon the needle-arm. The opposite end of said lever is extended some distance beyond the point of pivotal support and is made relatively broad, with a curved end margin e', so as to have 40 an approximately segmental form. The upper portion of the pendulum-link B is provided at its rear side with extensions b b', upon which are formed integral tappet-ears b² b³, respectively, which are bent to stand at right 45 angles outwardly from the plane of the link, so as to stand in the path of the tappet-lever, at the upper and lower sides of the latter, respectively, and at such distances apart as to provide a determined amount of lost motion 50 between the lever and pendulum-link.

In order to regulate or vary the length of throw of the ruffler-blade, I provide means for, in effect, varying the width of that part of the tappet-lever which contacts with the tappet-shoulders. 55

F designates an eccentric-shaped tappet-block pivotally secured to the side of the tappet-lever in position to engage the tappet-shoulder b' of the pendulum-link. Said tappet-block is provided with novel and improved means for holding it in adjusted position, comprising an integral holding-arm f, which extends forward longitudinally of the tappet-lever, to the end thereof, and is provided with a returned end portion f', arranged to embrace the curved end margin of the lever, the curve of the latter being made con-

centric with the pivot f² of the tappet-block. In order to lock the holding-arm rigidly and securely in any exact position of adjustment, 70 I provide a set-screw f³, which is threaded through the holding-arm at a point opposite the returned end portion f', so as to impinge against and clamp the end of the tappet-lever between the end of the set-screw and said 75 returned portion. The shape or eccentricity of the tappet-block and its diameter are such that when in one position (in the present instance when the holding-arm is swung to its lowermost limit, although obviously the relation of the eccentricity to the pivot might be reversed) it will be wholly within the width of that part of the lever upon which it is mounted, with its upper margin flush with that of the lever; but as it is oscillated by 80 the swinging upward of the holding-arm its upper margin will be gradually projected above the edge of the tappet-lever in position to engage the upper tappet-shoulder b², and by reducing the amount of lost motion im- 85 part a longer throw to the ruffler-blade. 90

In order to insure both delicacy of adjustment and positiveness in holding capacity, the end of the set-screw f³ is desirably made pointed, so as to seat itself slightly in the surface against which it acts, although the pointing of the screw is not indispensable, an ordinary screw holding firmly. It may be noted in this connection that the improved means of holding the tappet-block in adjusted position may be adapted to rufflers of other construction and, in fact, to other sewing-machine attachments generally. 95

In the operation of the ruffler the ruffling-blade upon each reciprocation gathers a certain length of the ruffling-strip and forces it in the form of a fold or gather between the presser-foot of the ruffler and the separating-blade. One of the essentials of a successful ruffler is that the fold when thus formed by 105 the feeding-in movement of the ruffling-blade shall be firmly gripped and held frictionally, so as not to be withdrawn by the return movement of the blade, it being understood that while the blade does not begin its retracting movement until after the needle has entered the fabric, yet the blade being much wider than the needle the fold must be held throughout the whole width of the blade or the cloth is liable to be drawn back on both 110 sides of the needle, although held at one point by the latter. To prevent this, the present invention contemplates the provision of an improved presser-foot G, made of resilient sheet metal and comprising an upper part g, 115 which is rigidly secured at its forward end to that part of the main frame through which the needle-aperture x is formed and which at its rear edge is doubled on itself to form a returned portion g', that extends forward beneath the upper part g at a little distance therefrom. The free front end will then yield readily as the fabric is forced beneath the foot by the ruffler-blade, while its rear or 120 125 130

doubled and less resilient portion will maintain a continuous pressure on the fabric and hold the latter from being drawn back by the ruffler-blade when the latter is retracted. In practice I find it desirable to extend the free end of the spring foot-blade slightly beyond the needle-aperture α or throat of the ruffler, as best indicated in Figs. 1 and 2. In order to lessen the tendency to release the fabric in rear of the needle by the thrusting in of the ruffler-blade and tuck, I set up that portion of the foot which overlies the end of the separating-blade and receives the fold of the ruffle slightly above that portion immediately in rear thereof, so that when the fold and ruffler-blade are underneath the spring-foot the portion of the foot in rear of the fold will still hold the fabric beyond or in rear of the needle.

One of the chief characteristics of the present invention is the peculiar manner in which the ruffle is formed and sewed. So far as I am aware rufflers have heretofore always been so constructed and operated that the crimp or gather was formed immediately beneath the needle, so that the latter in descending pierced and sewed through the fold itself instead of between the latter. I have discovered that a very much smoother and more uniform ruffle is produced when each fold or crimp is so laid that the sewing points or ends of the stitches are always placed between the successive folds, and I have further discovered that it is practicable to do this with all reasonable degrees or variations of fullness by so constructing the ruffler that the blade thereof will always begin to gather the fabric at a point approximately coincident with the line of the needle and will form the ruffle entirely in rear of this line, differences in fullness or size of the gathers being formed entirely by varying the throw of the ruffler-blade beyond the needle.

Referring to Fig. 2, in which the ruffling-blade is shown as fully retracted, it will be seen that its free acting end stands just in line or vertically beneath the throat-and-needle point, which starting position will be always the same in all degrees of fullness, inasmuch as the movement of the adjusting tappet-block serves only to vary the throw of the blade in the upstroke of the tappet-lever. It will also be seen by reference to said Fig. 2 that the last-formed ruffle or fold is located in rear of the needle a distance equal to the throw of the ruffler-blade and that that part of the ruffling-strip pierced by the needle is practically flat and ungathered. As the needle rises and after it has left the fabric that portion intervening between the point at which the preceding stitch pierces it is gathered by the feeding-in movement of the ruffler-blade and held in this position just at the moment when the tension on the threads draws the stitch tight, as seen clearly in Fig. 4. In other words, the stitch is fully formed in the cloth before the formation of the ruffle

begins, but the stitch is not tightened until after the ruffle is fully formed, whereby there is but one stitch to each plait and that stitch is invariably at a point between each plait, and the ruffling-blade is not withdrawn until the stitch is tightened, the result being that the ruffling-blade is prevented drawing the goods with it in making the back stroke. Obviously this results in laying the upper thread of the stitch smoothly over each ruffle or fold and also in placing the end of each stitch exactly between the folds. It is to be noted that the feeding forward of the fabric by the feed-dogs of the machine brings the band or underlying fabric (in case the ruffle is simultaneously sewed to the fabric, as is usual) into proper relation to the gather before the tension tightens the stitch, the fabric below the separating-plate following up, as it were, the gather formed by the ruffling-blade at each stitch before the stitch tightens. Obviously it is necessary to slot the ruffling-blade from its acting edge forwardly opposite the needle a distance sufficient to permit the longest throw of said blade rearwardly without engaging the needle, as shown clearly at c in Fig. 3.

The ruffler is shown as provided with the usual guides or gages for guiding the several strips of fabric in the usual way, comprising the piping-slots h h' and ruffler-strip slot h^2 , formed in a single plate H , secured to the upper side of the ruffler-blade body, and the band-guide h^3 , formed in the separating-plate support.

The operation of the ruffler constructed as described has been sufficiently indicated in connection with the description to be fully understood, and need not, therefore, be repeated. It is to be noted, however, that the peculiar method of supporting the ruffling-blade enables the latter to reciprocate in a substantially rectilinear path without the employment of guideways or guides of any nature, thus obviating all rubbing together of parts, which not only creates an unnecessary amount of friction, but leads to the rapid deterioration or wearing out of the ruffler, thereby preventing accurate ruffling, for it will be obvious that when the parts rubbing together become dry they commence to wear and cut, which added friction varies the fullness of the ruffle, making it impossible to do regular and even work. This is one of the most serious defects of the rufflers now in use. This result is the more certain to happen because of the disinclination of operators to apply oil to the wearing parts, where it is more than likely to soil the fabric. I am aware that it is not broadly new to support a ruffling-blade upon a pendulum or link support; but heretofore this has been done by supporting the blade from a single pendulum-link and guiding its free end by the use of fixed guides upon the frame, thus failing to remedy the difficulty. It is further obvious that when but a single pendulum-link sup-

port is used the path of reciprocation of the ruffler-blade will not approach a rectilinear motion. In this connection it is to be noted that while it is desirable that the standards from which the pendulum-links are supported be located at a considerable distance apart longitudinally, yet it is not essential that they be located as shown herein, but, on the contrary, they may be differently located to adapt the ruffler to different machines or otherwise.

The advantages of forming the ruffle in the peculiar manner incident to the present device have been stated in connection with the description of the manner in which the ruffle is formed.

While I have herein shown and described what I deem to be a preferred embodiment of my invention, yet it will be understood that the details thereof are susceptible of modification without departing from the invention, and I do not, therefore, wish to be limited to the precise details shown except as made the subject of specific claims.

25 I claim as my invention—

1. In a ruffler, the combination of a pair of separated pendulum-links, separate pivots suspending said links, means supporting said pivots, a ruffler-blade, and pivots, each forming a connection of its own between said blade and links, and means for actuating said blade and links, substantially as described.

2. In a ruffler, the combination with a main frame of a pair of pendulum-links, pivots therefor separated from each other on said frame, a ruffler-blade pivotally secured to the links and supported thereby, and means for reciprocating said blade, substantially as described.

3. In a ruffler, the combination with a main frame, a ruffler-blade, a pair of links pivotally depending from the opposite ends of said main frame and forming a vibratory support for a ruffling-blade, the toothed end of which is suspended at a point between said links and an actuating-lever for reciprocating said blade, substantially as described.

4. In a ruffler, the combination with a main frame, of a pair of pendulum-links pivotally supported from said main frame, a ruffling-blade pivotally suspended at a point between said links, and means for reciprocating said blade and adjusting the movement thereof, substantially as described.

5. In a ruffler, the combination with a main frame provided with upstanding supports separated from each other, of a pair of pendulum-links respectively pivoted to each of said supports, a ruffler-blade pivotally secured to the depending ends of the links and suspended therefrom, and means for oscillating one of said links to reciprocate said ruffler-blade, substantially as described.

6. In a ruffler, the combination with a main frame provided with upstanding supports arranged opposite each other at a distance apart, a pair of pendulum-links pivotally

supported from said upstanding supports, a ruffling-blade pivotally supported by said links, an actuating-lever and a pivot therefor common to one of said supports, means reciprocating said blade and for regulating its length of stroke, substantially as described.

7. A ruffler, comprising a frame approximately L-shaped in its main portion, standards at opposite ends thereof, pendulum-links respectively pivotally depending from each standard, a ruffler-blade support pivotally suspended by and at a point between said links and arranged within the angle of the L-shaped frame, a ruffler-blade carried by said support, a tappet-lever pivoted to one of the standards, tappet-shoulders upon one of the adjacent pendulum-links in the path of oscillation of said tappet-lever, and means for varying the amount of lost motion between tappet-lever and pendulum-link, substantially as described.

8. In a sewing-machine attachment, the combination with an actuating-lever adapted to engage the needle-bar, of pivoted adjusting devices on said lever, and means for locking said devices in adjusted position, comprising an arm pivotally mounted on the lever, a marginal edge on the lever concentric with the pivot-point, and a set-screw threaded through the pivoted arm and impinging upon said concentric edge of the lever, the extremity of the arm being folded around said edge opposite said screw, substantially as described.

9. In a ruffler, the combination with a tappet-lever and a tappet-block pivotally mounted thereon, of means for adjustably locking said tappet-block in position comprising a holding-arm connected with the tappet-block, a segment-surface upon said tappet-lever, over which said holding-arm is arranged to sweep, having a marginal edge formed concentrically with the pivot of the holding-arm and around which concentric margin the free end of the holding-arm is returned, and a set-screw threaded through said holding-arm and arranged to clamp the edge of the segment between its impinging end and the returned end of the holding-arm, as and for the purposes described.

10. In a ruffler, the combination with the main frame, a ruffler-blade provided with a toothed end and movably mounted in said frame, means permanently limiting the back stroke of the toothed edge of said blade to a point on a line across said edge and through the needle-hole, means reciprocating said blade to form a ruffle after the needle has made a stitch, and means withdrawing said blade from the formed ruffle after the stitch is fully tightened, substantially as described.

11. In a ruffler the combination with the main frame, a ruffling-blade provided with a toothed end and movably mounted in said frame, means permanently limiting the back stroke of the toothed edge of said blade to a point on a line across said edge and the neo-

dle-hole, means of reciprocating said blade to form a ruffle after the needle has made a stitch, means withdrawing said blade from the formed ruffle after the stitch is fully tightened and means for varying the forward stroke of the ruffling-blade, substantially as set forth.

12. In a ruffler, the combination with the main frame, of a ruffling-blade movably mounted thereon with its toothed end permanently stopping on a line transversely thereof and approximately across the needle-hole when the blade is retracted, means for reciprocating said blade to project its toothed end beyond the needle-hole, and means for varying the forward stroke of the blade, substantially as described.

13. In a ruffler, the combination with a main frame, provided with a pair of depending pendulum-links, parallel with and separated from each other, of a ruffling-blade pivotally supported by said links, an actuating-lever for reciprocating said ruffling-blade, the cloth-engaging end of the ruffling-blade extending approximately to the path of the needle, when the blade is retracted, and an adjustable contact applied in connection with the actuating-lever for varying the amount of advance of the blade beyond the needle on the upstroke of the lever, substantially as described.

14. In a ruffler, the combination with a main frame, of parallel links pivoted to said frame at points separated from each other, a ruffling-blade pivotally supported from said links, an actuating-lever for advancing and returning the ruffling-blade through the medium of contact-points, and an adjusting-lever having means to engage the contact-point which is engaged on the upstroke of the actuating-lever so as to advance the ruffling-blade a greater or less distance and as to engage the contact-point which is engaged on the downstroke of the actuating-lever so as to invariably return the blade to a position where the points of its teeth will be substantially coincident with the path of the needle transversely to the line

of motion of the blade, substantially as described.

15. In a ruffler, the combination with the frame-plate provided with two upstanding supports, of a ruffling-blade carrier arranged adjacent to one of said supports, a link pivotally suspending the ruffling-blade from that support, another link depending from the other support, an extension rigid with the ruffling-blade support projecting across the frame-plate and pivotally suspended from the second link, and a ruffling-blade secured to said carrier, substantially as described.

16. In a ruffler, the combination with an L-shaped frame-plate provided with an upstanding support at the inner side of the leg of the L, a similar support at the foot of the L, a ruffling-blade carrier mounted in the angle of the L, a link depending from the inner side of the first support and pivotally suspending the ruffling-blade carrier, an extension in the carrier projecting across the frame-plate to the opposite side of the second support, a link depending from the latter and pivotally supporting said extension, and a ruffling-blade secured to said carrier, substantially as described.

17. In a ruffler, the combination with a frame-plate A provided with a struck-up portion *a* projecting rearwardly from the foot of the plate and adapted to be attached to a sewing-machine, an upstanding support A' at the inner edge of the frame-plate, a similar support A² at the opposite edge of the struck-up portion *a*, the ruffling-blade, pendulum-links pivoted to said supports and to the ruffling-blade, substantially as described.

In testimony that I claim the foregoing as my invention I affix my signature, in presence of two subscribing witnesses, this 27th day of November, A. D. 1899.

WINSLOW R. PARSONS.
